UNITED STATES PATENT OFFICE.

HARRY E. MORTON, OF BOSTON, MASSACHUSETTS.

VACUUM-BREAKER.

1,204,301.

Specification of Letters Patent. Patented Nov. 7, 1916.

Application filed March 6, 1913. Serial No. 752,288.

To all whom it may concern:

Be it known that I, HARRY E. MORTON, a citizen of the United States, residing at Boston, in the county of Suffolk and State of Massachusetts, have invented an Improvement in Vacuum-Breakers, of which the following is a specification.

This invention relates to vacuum-breakers adapted to open a vacuum-space to the atmosphere and thereby destroy the vacuum between a jet-condenser and a steam-engine, in case the condensing-water rises abnormally in the condenser and starts to flow back through the exhaust steam-pipe to the engine, which, if permitted to continue will wreck the engine.

The object of the invention is to produce a more efficient and reliable device than has heretofore been constructed.

The invention involves the principle of utilizing the weight of the condensing-water which rises in the condenser, and starts to flow back through the exhaust steam-pipe, for operating suitable means to open an air inlet-valve, thereby to open the vacuum-space to the atmosphere and to destroy the vacuum.

In the embodiment of my invention here shown for illustration, a receptacle in open communication with the vacuum-space is employed, which is arranged to receive the condensing-water which flows back from the condenser and by the weight thereof is caused to descend, as for instance, the receptacle may be made with an open top and arranged in upright position in an upright portion of the exhaust steam-pipe, or other part of the vacuum-space, adapting it to receive the condensing-water; and said receptacle is pivotally or otherwise supported, admitting of its being moved downwardly by the weight of the condensing-water. An air inlet-valve is arranged to open the vacuum-space to the atmosphere, thereby to destroy the vacuum, and said valve is arranged for operation by and upon a downward movement of the receptacle to open the vacuum-space to the atmosphere. Means are also preferably provided for insuring a positive opening movement of the air inlet-valve when started by and upon a downward movement of the receptacle, and said means may and preferably is adapted to be operated manually, at a subsequent time, to restore the air inlet-valve to closed position. The receptacle is usually provided with a

small hole at the bottom which allows the condensing-water to slowly escape, so that, when it has moved downward and has caused the air inlet-valve to open the vacuum-space to the atmosphere, it will, after a short period of time, automatically resume its normal elevated position, and, therefore, constitutes a self-restoring actuator for the air inlet-valve.

Figure 1 is a conventional view illustrating a portion of an engine, jet-condenser, pump associated with said jet-condenser, and a vacuum-breaker embodying this invention, arranged in the exhaust-steam pipe. Fig. 2 is an enlarged vertical longitudinal section of the vacuum-breaker illustrated in Fig. 1. Fig. 3 is a front elevation of the same. Fig. 4 is a section on line 4—4, Fig. 2. Figs. 5 and 6 are enlarged detail views of an inlet-valve which may be employed. Fig. 7 is a front view of said valve, and, Fig. 8 is an enlarged sectional detail of the valve.

For the purpose of illustrating my invention the engine 10 is here shown as associated with a jet-condenser 12, pump 13, exhaust-steam pipe 14, leading from the engine-cylinder to the jet-condenser, all of which may be of any usual or suitable construction.

The vacuum-breaker is here shown as connected with the exhaust-steam pipe 14. As here shown, 20 represents the shell or case of the same, which is made of suitable size and shape to be connected in and form a part or section of the exhaust-steam pipe, but it may be otherwise arranged for connection therewith. Said shell or fitting 20, has a large opening at the side or elsewhere, which is closed by a flanged cap 22 having an interior recess, and said cap has an opening 24 to receive a suitable air inlet-valve, and, as here shown, said opening has a valve-seat 25 for said valve. The opening 24 is of sufficient size to enable the vacuum to be quickly destroyed. As the opening is made quite large a large valve is required and as said valve is held on its seat firmly by the air pressure, considerable power is required to lift it, hence a valve of peculiar construction is preferably employed, one having a small auxiliary-valve in connection with it. The inlet-valve here shown consists of a valve-plate 26, for engagement with the seat 25, and has on its under side several downwardly extended wings 27, and said plate has a center-hole through it for an auxiliary-

valve, which hole is formed with a seat for said auxiliary valve.

The auxiliary valve consists of a stem 30, extended through the center-hole in the valve-plate 26 having its lower end portion of a reduced diameter relative to its upper end portion and having a conical seating-portion 31, at the junction of said upper and lower end-portions, which is adapted to engage the valve-seat formed in the valve-plate. Said lower end-portion extends downward a short distance and terminates just above an actuating-device. The auxiliary valve-stem 30 is movable longitudinally upon the initial movement of the actuating-device to open the way through the center of the valve-plate, and upon further movement of said device a collar 35 screwed or otherwise arranged on said stem engages the lower ends of the wings of the valve-plate 26 and acts to lift said plate from its seat, thereby opening the large way. The area of the valve-plate 26 is reduced, so that less power is required to lift said valve-plate to open the way than would otherwise be the case, since the vacuum is partially broken by opening the auxiliary valve. My invention, however, is not limited to the employment of an air inlet-valve of any particular construction, or to an inlet-valve having an auxiliary-valve in connection with it, or to the employment of a main-valve and auxiliary valve associated together as here shown or otherwise for successive operation.

The actuating-device for the inlet-valve is here shown as a lever or yoke 40, pivotally supported on any suitable bearings for easy movement, having a receptacle 41 at one end arranged in the shell 20, in the path of the condensing-water, and having a counter-weight 42, arranged beneath the inlet-valve. Said receptacle is normally held in elevated position and against vibration by the counter-weight 42, engaging a limiting-stop 43, which is arranged on the shell. Said receptacle has a small hole through it, at its bottom, for the escape of the contents thereof, although as the receptacle is quite large and the hole is quite small, considerable time is required for the condensing-water to escape in case the receptacle is filled, but in ordinary use the hole is of ample size to enable any water of condensation which may enter it to escape. When the condensing-water flows back through the exhaust-steam pipe it enters the receptacle and its weight added to that of the receptacle causes the receptacle to descend, thereby lifting the counter-weight against the lower end of the stem 30, and thus acting to move said stem longitudinally and open the valves. The counter-weight may have upon its upper side a spherical portion and the lower end of the collar 35 may have a spherically formed

end to be engaged by the spherical portion on the counter-weight. The vacuum-breaker is here shown as arranged in a vertical portion of the exhaust-steam pipe, as near the jet-condenser as possible, so that the receptacle will occupy a position to receive the condensing water which flows back from the jet-condenser, and hence will operate to open the inlet-valve quickly and destroy the vacuum before the condensing-water reaches the cylinder.

The shell 20 containing the receptacle 41 is formed with flanges at its ends adapting it to be connected in and form a section of the exhaust-steam pipe, and the openings at both ends of said shell correspond with the internal diameter of said pipe, but that portion of the shell between said openings is made of much larger diameter to admit of a receptacle being employed having its opening at the top as large as or larger than the opening at the top of the shell, and also to admit of the passage around said receptacle being of substantially the same area as the area of said pipe, so that ample space is afforded for the passage of exhaust-steam around or by the receptacle. A flange 21 is formed around the interior of the opening at the top of the shell 20, which extends downwardly for a short distance to form a nozzle for directing the condensing-water into the receptacle which is arranged directly beneath it. This form of actuating-device is positive in action, being operated entirely by the weight of the water.

It is designed that the inlet-valve when once opened shall remain open until closed by hand, and to provide for the accomplishment of this result the stem 30, is slotted at 50, to receive the end of the arm 51, of a bell-crank lever, which is pivoted at 52, the other arm 53 of said lever extending upward and having a weighted end, adapted to be engaged by hand. Said weighted bell-crank lever, however, is employed not only as a means to hold the inlet-valve open, and to provide for closing it when operated manually, but also as here shown, acts to open or assist in opening the inlet-valve when once tripped. In this particular, as the stem 30 is moved upward by the actuating-device, the bell-crank lever is moved by it until the weighted end-portion passes from the left to the right of a perpendicular, this being the initial movement of said lever, when it will be noted that said weighted end-portion falls by gravity, this being the subsequent movement of the lever and upon its subsequent movement its arm 51 which normally engages the lower end of the slot 50 moves upward quickly and engages the upper end of said slot, thereby adding its weight and momentum to assist in further lifting the stem and also in opening the main valve-plate. Said bell-crank lever then acts to

hold the valves in open position until its weighted arm is lifted by hand and the valves consequently closed. Other means, however, may be employed for accomplishing this result in lieu of the particular means here shown.

As the arm 53 of the bell-crank lever is arranged outside of the shell for engagement by hand, it is accessible at all times for 10 operation by hand, so that the valves may be opened whenever desired for testing purposes. This provision enables the valves to be inspected and cleaned and repaired if necessary.

15 Herein the vacuum-breaker is represented as included directly in and forms a part of the exhaust pipe, and therefore is arranged between the jet-condenser and engine, but it is intended by this term to include any other 20 location of the vacuum-breaker, whereby it is adapted to receive condensing-water which flows back from the jet-condenser, said term being employed more particularly to correlate the vacuum-breaker with the elements 25 with which it coöperates.

I claim:

1. A vacuum-breaker consisting of an enlarged pipe-section adapted to be arranged in upright position in the main exhaust steam-pipe between a jet-condenser and engine, a 30 movable receptacle normally arranged in a predetermined elevated position therein, to permit free passage of the exhaust steam by it and to receive condensing-water which 35 flows back from the jet-condenser, means associated with said receptacle for holding it in its elevated position and against vibration, which permits downward movement thereof when overcome by the weight of the 40 condensing-water, a non-return air inlet valve arranged for operation by the downwardly moving receptacle, said receptacle having a leak-opening permitting escape of the condensing-water and the return of the 45 receptacle to normal position independently of the valve, whereby the valve remains open.

2. A vacuum-breaker consisting of an enlarged pipe-section adapted to be arranged 50 in upright position in the main exhaust steam-pipe between a jet-condenser and engine, a movable receptacle normally arranged in a predetermined elevated position 55 therein, to receive condensing-water which flows back from the jet-condenser through said pipe, said pipe-section being of much larger diameter than the receptacle to permit free passage of the exhaust steam by it, means associated with said receptacle 60 for holding it in its elevated position and against vibration, which permits downward movement thereof when overcome by the weight of the condensing-water, a non-return air inlet-valve arranged for operation 65 by the downwardly moving receptacle, said

receptacle having a leak-opening permitting escape of the condensing-water and the return of the receptacle to normal position independently of the valve, whereby the valve remains open, and hand-engaging means associated with said valve for returning it to closed position. 70

3. A vacuum-breaker consisting of an enlarged pipe-section adapted to be arranged in upright position in the exhaust steam 75 pipe between a jet-condenser and engine, a movable receptacle normally arranged in a predetermined elevated position therein to provide a free passage for the exhaust steam by it and to receive condensing-water which 80 flows back from the jet-condenser through said pipe, means associated with said receptacle and arranged in said section for holding it in its elevated position and against vibration, which permits downward movement thereof when overcome by the weight of the condensing-water, a non-return air inlet-valve independent of said receptacle and its holding-means, which is arranged 85 for engagement with said holding-means for 90 operation upon downward movement of the receptacle and for independent return of said receptacle to normal position, and hand-engaging means associated with said valve for returning it to closed position independently of the receptacle. 95

4. A vacuum-breaker consisting of an enlarged pipe-section adapted to be arranged in upright position in the exhaust steam pipe between a jet-condenser and engine, 100 having an opening in its side, and a removable recessed wall arranged over said opening, a pivoted counter-balanced receptacle arranged in said section to permit a free passage of the exhaust steam by it and to receive condensing-water which flows back from the jet-condenser, the counterweight being extended into the recess of said wall, and an air inlet-valve arranged on said wall 105 above said counterweight, to be engaged thereby upon a downward movement of the receptacle. 110

5. A vacuum-breaker consisting of an enlarged pipe-section adapted to be arranged in upright position in the exhaust steam 115 pipe between a jet-condenser and engine, having an opening in its side and a removable recessed wall arranged over said opening, a pivoted counter-balanced receptacle arranged in said section to permit a free 120 passage of the exhaust steam by it and to receive condensing-water which flows back from the jet-condenser, the counterweight being extended into a recess of said wall, the side opening being of sufficient area to admit of the passage through it of the receptacle, an air inlet-valve arranged on said wall above said counterweight, to be engaged thereby upon a downward movement 125 of the receptacle. 130

6. A vacuum-breaker consisting of an enlarged pipe-section adapted to be arranged in an upright portion of the exhaust steam-pipe between a jet-condenser and engine, 5 a pivoted member arranged therein, a receptacle borne by one end of said member which affords a free passage for the exhaust steam by it and receives the condensing-water which flows back from the jet-condenser, a stop against which said receptacle is normally held, a counterweight associated with the other end of said member, for holding the receptacle in elevated position 10

against said stop, and an air-inlet valve arranged to be engaged and lifted by said member upon a downwardly swinging movement of said receptacle to open the vacuum-space to the atmosphere. 15

In testimony whereof, I have signed my name to this specification, in the presence of 20 two subscribing witnesses.

HARRY E. MORTON.
